UNITED STATES PATENT OFFICE.

ALBERT CASH, OF LEWISTON, MAINE.

BLOCK-LEVELER.

1,249,026.

Specification of Letters Patent. Patented Dec. 4, 1917.

Application filed September 25, 1916. Serial No. 122,100.

To all whom it may concern:

Be it known that I, ALBERT CASH, a citizen of the United States, residing at Lewiston, in the county of Androscoggin and State of Maine, have invented a new and useful Block-Leveler, of which the following is a specification.

The present invention appertains to surfacing machines, and relates more particularly to an appliance for planing, leveling and smoothing the block forming the base or bed of a clicking machine upon which the materials to be cut by dies is supported, the present device being an improvement over the surfacing machine disclosed in my Patent No. 1,148,499, granted August 3, 1915.

The present device is an attachment for a clicking machine for planing, leveling and smoothing the blocks thereof upon which the material is cut by means of dies, which after continued use cause the blocks to become ragged and in some cases gouged out.

In order to get the best results, it is very essential that the block of a clicking machine be perfectly smooth and level, and it is the object of the invention to provide a simple yet effective attachment for the arm of a clicking machine operable in a simple and efficient manner for surfacing the block, and in a manner far superior to ordinary means now used, such as a long file with handles at either end with which the leveling of a block is a laborious undertaking and more or less inefficient.

Another object of the invention is the provision of a block leveler which requires but little power to operate, which is light and easy to apply and remove, being readily applied from one clicking machine to another, and which will serve its office in a thoroughly practical, efficacious and serviceable manner.

With the foregoing and other objects in view, which will appear as the description proceeds, the invention resides in the combination and arrangement of parts and in the details of construction, hereinafter described and claimed, it being understood that changes in the precise embodiment of the invention herein disclosed, can be made within the scope of what is claimed, without departing from the spirit of the invention,

The invention is illustrated in the accompanying drawings, wherein:

Figure 1 is a plan view of a clicking machine showing the attachment applied, a portion being broken away. 55

Fig. 2 is a side elevation of the clicking machine and the attachment.

Fig. 3 is a section on the line 3—3 of Fig. 1. 60

Fig. 4 is an enlarged section on the line 4—4 of Fig. 1, illustrating the motor in elevation.

Fig. 5 is a perspective view of the cutter, 65 a portion being broken away.

Fig. 6 is a view of a modified form of cutter bit.

In the drawings, there is illustrated an ordinary clicking machine 1, embodying the frame or stand 2, carrying the horizontal block or bed 3 for supporting the material, and also embodying an oscillatory and vertically movable weighted arm 4 above the block 3. The machine is provided with means for raising the horizontally swinging arm or weight 4 and then liberating the same so that it will impinge with great force upon the die (not shown) seated upon the material disposed on the block 3, to cause the die to cut the material. As illustrated, the arm 4 is provided with lower outstanding flanges or wings 5 arranged in a horizontal plane and projecting in opposite directions, which flanges are employed for the application of the present attachment to the clicking machine. 75 80 85

The attachment comprises a body or casting 7 adapted to be disposed at one side of the arm 4 parallel therewith, and having a longitudinal slot 8 opening at one side of the body 7 for receiving one flange or wing 5, to apply the body 7 to the arm 4. The body 7 is provided with a rigid arm 9 extending at an angle therefrom to lie underneath and extend transversely across the lower surfaces of the flanges 5. The end of the arm 9 has a reduced stem 10 upon which a wing nut 11 is threaded, and a U-shaped attaching clip 12 straddle the edge 100 of the flange 5 remote from the body 7, the upper limb 13 of the clip 12 being secured upon said flange 5 by means of a screw 14 or other securing element, and the

- lower limb 15 of the clip supporting the end of the arm 9. The stem 10 extends through the intermediate portion of the clip 12 and the nut 11 bears against said clip, whereby 5 when the nut is tightened, the body 7 is drawn tightly into place to hold it firmly upon the respective flange 5 of the arm 4. Thus, by means of the clip 12 and nut 11, the arm 9 of the body 7 is connected to that 10 flange 5 remote from the body, and the body is drawn tightly into place.
- The body 7 is provided with an upper longitudinal groove 16 of T-shaped cross section, and said body is provided at that side 15 remote from the arm 4 with a lower outstanding flange 17 provided with an upturned lip 18 forming a groove 19 between said lip and the body. A slide 20 is disposed in a vertical plane against that side of the 20 body 7 opposite to the arm 4 and is provided at its upper edge with a portion 21 overhanging the body and provided with a tongue 22 of T-shaped section working within the groove 16. The lower edge of the 25 slide 20 has a tongue 23 working in the groove 19, whereby the two tongues of the slide in engaging the body will guide the slide 20 for longitudinal movement of the body 7 parallel with and at one side of the 30 arm 4. The slide 20 is provided adjacent to its lower edge with an outstanding horizontal shelf 24 provided with a relatively wide groove 25 in which a supporting bar or bracket 26 is secured by means of bolts, 35 screws, or other securing elements, the inner end of the bar 26 projecting from the shelf 24.

An electric motor 27 is secured upon the inner projecting end of the bar 26 with its 40 armature vertical, and the armature shaft 28 of the motor projects downwardly through the bar 26 and has a collar 29 thereon below said bar. A cutter or planer 30 is fitted upon the lower terminal of the shaft 28 and is secured against the collar 29 by means of a nut 31 or other retaining element engaged upon the lower end of the shaft 28 and bearing upwardly against the cutter. The cutter 30 rotates in a horizontal 45 plane above the block 3.

The cutter 30 embodies a horizontal disk 31 having a central aperture 32 for receiving the shaft 28, and provided with a plurality, in this case three, of rectangular apertures 33 in which the shanks 34 of the cutter bits 35 are disposed, said shanks being of rectangular cross section and fitting slidably in said apertures 33. The shanks are clamped within said apertures by means 55 of set screws 36 threaded into the periphery of the disk 31, and when said set screws are loosened, the cutter bits can be adjusted. Said bits require a minimum amount of power to actuate them. The bits 35 project 60 downwardly from the disk 31 to engage the

upper surface of the block 3, and decrease in thickness and length from their relatively wide forward edges, to provide sharp ends for shaving the surface of the block.

Vertical adjusting screws 38 are threaded 70 within the body 7 below the groove 16, and are accessible from above, whereby they can be rotated by means of a screw driver or other suitable implement. The screws or clamping means 38 project downwardly into 75 the slot 8 and are adapted to seat upon one flange or wing 5 of the arm 4, whereby to adjustably support the body 7. This permits of the vertical adjustment of the body for adjusting the cutter likewise, in order 80 that the cutter can be adjusted for shallower or deeper cuts at different portions of the block.

In operation, the body 7 can be readily attached to the arm 4, as above indicated, 85 when it is desired to surface the block 3, and the motor 27 can be connected by a cord with the lighting or power wires of the shop, whereby to operate the motor, so that the cutter 30 will be rotated. The arm 4 is 90 then adjusted vertically in order that the cutter 30 will properly act upon and level the surface of the block 3. The slide 20 is then slid back and forth along the track or guides of the body 7 and the arm 4 is swung, 95 whereby the cutter will act upon the entire surface of the block 3 to level the same. The cutter has a range of movement over the entire surface of the block 3, due to the swinging movement of the arm 4, and the 100 sliding movement of the slide 20 parallel with said arm at one side thereof. The cutter rotates about a vertical axis whereby the cutter in being moved over the surface of the board and rotating simultaneously, will 105 provide an efficient surfacing cut, and the cutter requires but minimum power to operate it. The attachment is light in weight, and can be readily taken from one machine and applied to another, and has other obvious advantages.

In Fig 6, a modified form of cutter bit is illustrated, the bit being designated 35' and being arranged in an inclined or oblique position, together with its shank 34'. The 115 chisel edge 37' of the bit 35' is arranged at an oblique position relative thereto to be disposed in a horizontal plane while the bit is applied to the body or disk of the cutter in an inclined position.

Having thus described the invention what is claimed as new is:—

The combination with a clicking machine having a block, and a horizontally swinging arm above said block having opposite outstanding flanges, of a body disposed at one side of said arm and having a longitudinal slot receiving one of said flanges, the body having means extending under said flanges and engageable with the other flange to hold 120

the body against the arm, clamping means carried by the body to bear against the first mentioned flange of said arm, the body having a lower longitudinal outstanding flange at that side opposite to the arm and having an upper longitudinal groove above the first mentioned flange of said arm and slot of the body, a slide bearing against said side of the arm having means at its lower edge engaging the flange of the body to hold the slide thereagainst, the upper edge of the slide having an overhanging portion engag- 10

ing in said groove, the slide having an outstanding shelf, and means carried by said shelf for leveling the upper surface of said block. 15

In testimony that I claim the foregoing as my own, I have hereto affixed my signature in the presence of two witnesses.

ALBERT CASH.
